UNITED STATES PATENT OFFICE.

THEODOR WILHELM, OF ZURICH, SWITZERLAND.

STOPPER FOR BOTTLES.

Application filed October 28, 1926, Serial No. 144,722, and in France March 6, 1926.

My invention relates to stoppers of bottles and has for its object the arresting of the stoppers for bottles.

Reference is to be had to the accompanying drawing in which—

Figures 1 and 2 show a stopper with a spring as an arresting device, and the head of the stopper rests on a seat.

Figure 3 shows a stopper similar to the construction of Figures 1 and 2, but a conical surface of the circumference closes the opening of the bottle.

Figures 4 and 5 show a stopper similar to the construction of Figures 1 and 2 but besides of a spring there is an elastic ring as an arresting device.

Figure 6 shows a stopper, which is equipped with only an elastic ring as arresting device.

According to Figure 1 the top of the bottle 20 is equipped with a seat 7, on which the head 8 of a stopper rests. The stopper consists of a cylindrical part and a round head of solid material, which cannot be damaged by acid and which does not transmit the heat. The 25 stopper carries a bushing 10 with threads for the bolt 2. The latter is connected to the lever 1 by the pin 19. The spring 16 and the washer 21, which is made from material, which does not transmit the heat, are 30 placed around the bolt 2.

According to Figure 1 the stopper 12 is placed into the opening of the bottle and the lever 1 has the position shown in Figure 35 1. As soon as the lever is brought into the position shown in Figure 2, the washer 21 is pressed downward and the spring 16 is pressed against the wall of the bottle, whereby the stopper 12 is arrested in its position. Figure 3 shows the same construction 40 only the upper part 4 of the bottle does not show the seat 7. The opening of the bottle is equipped with a conical seat 5. The circumference of the stopper 13 is formed with a conical surface 6, corresponding to the conical seat 5, that the conical surface 45 6 can sit on the seat 5. The bushing 11 carries threads and is driven into the stopper 13. As soon as the surface 6 is pressed into the seat 5, the lever 1 is pushed downward 50 and the spring 16 is pressed against the wall of the bottle by the washer 21 and therefore the stopper 13 with its head 9 is kept in its position. According to Figures 4 and 5 the stopper 14 carries the head 15.

55 The spring 18, the washer 21 and the elastic

ring 17 are placed around the bolt 2. According to Figure 5, the lever 1 pushes the washer 21 down, which presses the spring 18 against the elastic ring 17, which will be pressed against the wall of the bottle by the 60 spring.

Figure 6 shows a construction without spring 18, where the elastic ring 17 is expanded and is pressed alone against the wall of the bottle for arresting the stopper 22 in 65 its position. The stopper is placed into the opening of the bottle with only a little play. In case a bottle with acid will be placed horizontally the stopper 22 must be made from material, which cannot be damaged by acid. 70 At the same time the stopper must be placed into the opening of the bottle with very little play, that no acid or only a little bit can reach the elastic ring 17, which otherwise would get destroyed. The cylindrical part of the stopper 75 should fill out the space of the opening of the bottle, so that no liquid, acid etc. may reach the elastic ring 17. If acid reaches the elastic ring 17 the latter will be destroyed. The position of the stopper is fixed by the elastic 80 ring 17, which is pressed against the wall of the bottle by the washer 23, which exerts a pressure on top of the ring 17 by the lever 1. By the pressure on top, the ring expands and is pressed against the wall of 85 the bottle. If the wall of the elastic ring 17 is very small it might happen, that, pressing the washer 23 down by the lever 1, the wall of the elastic ring bends inside and does not rest against the wall of the bottle. 90 Therefore it is necessary, that the pin 2 fits very tightly into the hole of the washer 23 so that the air, which will be compressed as soon as the washer 23 will be pressed down, presses the wall of the elastic ring 17 tightly 95 against the wall of the bottle. The stopper 22 with the arresting device can be used for bottles with openings shown in Figures 1 and 4, this means, for valve seats and cylindrical opening.

As the stopper consists of a cylindrical part and a round head, made of solid material, the round head of the stopper can be used for bottles with a seat in the top of the bottle. At the same time the stopper can 105 be used for bottles, filled with acid, with a cylindrical hollow part on the top. If the bottle is filled with acid and placed horizontally the cylindrical part of the stopper prevents the acid from injuring the elastic 110

part of the arrester. Therefore the stopper can be used for any kind of bottles and any kind of liquids.

I claim:

- 5 1. Stopper made from material not transmitting the heat, the stopper fitted with a cylindrical part and a round head, a pin, fixed into the head of the stopper, a washer, fitting tightly around the pin, made from material not transmitting the heat, an elastic ring around the pin, an air tight chamber between elastic ring, washer and stopper, a lever on top of the pin, pressing the washer down, whereby the elastic expanding ring is pressed 10 against the wall of the bottle by the compressed air and the stopper is arrested in the bottle.
- 15

2. Stopper made from material not transmitting the heat, the stopper fitted with a cylindrical part and a round head, a pin, 20 fixed into the head of the stopper, a washer, fitting tightly around the pin, made from material, not transmitting the heat, an elastic ring and a spring around the pin, an air tight chamber between elastic ring, washer and stopper, a lever on top of the pin, pressing the washer down, whereby the elastic expanding ring is pressed against the wall of the bottle by the compressed air and the spring, which at the same time presses the 25 round head of the stopper down on its seat and the stopper is arrested in the bottle.

In testimony whereof I affix my signature.

THEODOR WILHELM.
